(57) **CLAIM**

The ornamental design for a hair removal device, as shown and described.

DESCRIPTION

FIG. 1 is a front perspective view of a hair removal device of the present invention showing my new design;
 FIG. 2 is a front side elevation view thereof;
 FIG. 3 is a back side elevation view thereof;
 FIG. 4 is a side elevation view thereof;
 FIG. 5 is another side elevation view thereof;
 FIG. 6 is a top plan view thereof; and,
 FIG. 7 is a bottom plan view thereof.
 The broken lines illustrate contour lines of the hair removal device and form no part of the claimed design.
